UNITED STATES PATENT OFFICE.

ROBERT PERLICK, OF MILWAUKEE, WISCONSIN.

RESERVOIR FOR OIL-STOVES.

1,307,878.

Specification of Letters Patent. Patented June 24, 1919.

Application filed November 7, 1918. Serial No. 281,478.

To all whom it may concern:

Be it known that I, ROBERT PERLICK, a citizen of the United States, and resident of Milwaukee, in the county of Milwaukee and

5 State of Wisconsin, have invented certain new and useful Improvements in Reservoirs for Oil-Stoves; and I do hereby declare that the following is a full, clear, and exact description thereof.

10 My invention relates to new and useful improvements in reservoirs adapted for use on oil stoves and of that type including a main bottle shaped supply receptacle, detachably mounted in inverted position over 15 an auxiliary constant level receptacle, the fluid level of which is determined by the bottom plane of the discharge neck of the main receptacle, which projects thereinto.

It is in general the object of my invention 20 to simplify and otherwise improve the construction of devices of this character.

A further object resides in the provision 25 of an arrangement whereby the main receptacle may be most readily mounted upon or removed from the auxiliary receptacle for replenishing the contents of said main receptacle, and an incidental object in this connection is to utilize the carrying members of the main receptacle as a supporting 30 means for the same.

A still further object is to provide an arrangement for supporting the main receptacle which insures a proper relative position thereof with respect to the auxiliary 35 receptacle whereby to insure the maintenance of a proper fluid level in the auxiliary receptacle, and whereby at the same time the receptacles are held in spaced relation to prevent capillary distribution of oil from 40 the auxiliary receptacle over the surface of the main receptacle.

With the above and other objects and advantages in view, which will be apparent as the description proceeds, my invention 45 resides in the novel features of construction, combination and arrangement of parts, as hereinafter more particularly described and defined by the appended claims.

In the accompanying drawings:

50 Figure 1 is an elevational view of one end portion of an oil stove having my improved reservoir associated therewith.

Fig. 2 is an elevational view of my improved receptacle, the lower reservoir and 55 connecting portions thereof being in section.

Fig. 3 is a plan view of the lower recep-

tacle, showing the supporting means for the main receptacle associated therewith, the main receptacle being omitted for the sake of clarity.

60 Referring now more particularly to the accompanying drawings, 5 designates one end portion of the frame of a conventional oil stove, in which is mounted a burner 6 of any suitable type requiring a constant supply 65 of oil fed thereto by the pipe 7. The supply pipe 7 is upwardly directed and communicates with the bottom of a pan-shaped auxiliary receptacle 8, which is supported by said pipe and by bracket arms 9 70 projecting outwardly from the stove frame and secured thereto.

The main receptacle 10 of the reservoir is formed of glass, as is usual, and is of a simple bottle shape, having a filling and 75 discharge neck 11 on which is threaded the usual narrow valve cap 12 having projecting therefrom a stem 12^a engaging with the bottom of the auxiliary receptacle to open the valve when the main receptacle is supported in proper inverted position thereover.

80 To procure this support of the main receptacle and at the same time to provide for a most ready manipulation of the receptacle, the intermediate portion thereof is provided 85 with an annular channel 13 formed in the present instance by offsetting the periphery of the receptacle inwardly, and a metallic band 14 is secured in this channel. Bail ears 15, carrying a bail 16, have their offset 90 end portions secured to the band, preferably by spot welding as the most economical means of attachment. Bowed handle strips 17 also have their end portions preferably 95 spot welded to the band at points spaced quadrantly with respect to the bail ears. The main receptacle may be thus readily manipulated for mounting it on or removing it from the auxiliary receptacle, and 100 may be conveniently carried. At the same time, the shoulders formed by offsetting the bail ears, and the sides of the handles are utilized to support the receptacle in operative position. A plurality of upstanding arms 18 have their lower ends inwardly 105 offset and secured to the outer periphery of the auxiliary receptacle 8, and the upper ends of the arms are connected by a supporting ring 19, said arms being preferably welded against the outer periphery of the 110 supporting ring. This ring is of such diameter as to snugly receive the main re-

ceptacle and seats the handle and bail ear shoulders, the bail being preferably of such dimensions that in this seated position it may drop around and lie under the auxiliary receptacle.

The top of the receptacle is preferably shielded and held by the downturned perimetal flange of a swinging shelf 20 carried by the adjacent end of the stove top.

10 An exceedingly simple arrangement has thus been provided for supporting the upper reservoir receptacle over the lower receptacle, in such manner that the proper relative positions of said receptacles is at all times maintained. It is noted that the auxiliary receptacle is of lesser diameter than the main receptacle and lies snugly under the exceedingly wide neck shoulder of the main receptacle, whereby it is protected particularly against access of foreign matter, and but a very slight space is afforded between the mouth of the auxiliary receptacle and the neck flange of the main receptacle, which serves to admit air to the auxiliary receptacle preventing the occurrence of a retarding vacuum therein. This spacing of the receptacles also prevents distribution of oil by capillary attraction from the auxiliary receptacle over the surface of the main receptacle.

15 20 25 30 What is claimed is:

1. A reservoir of the class described including a main support, an auxiliary receptacle carried thereby, arms extending upwardly from said auxiliary receptacle, an annular seating band carried by said arms,

35 a main receptacle insertible in said seating band, and support members carried by the intermediate portion of the periphery of the main receptacle to seat on said hand.

40

2. A reservoir of the class described including a main support, an auxiliary receptacle carried thereby, arms extending upwardly from said auxiliary receptacle, an annular seating band carried by said arms, 45 a main receptacle insertible in said seating band, support members carried by the intermediate portion of the periphery of the main receptacle to seat on said band, and a bail pivotally connected with the intermediate 50 portion of the periphery of the main receptacle and adapted to lie about the auxiliary receptacle.

55

3. A reservoir of the class described including a main support, an auxiliary receptacle carried thereby, arms extending upwardly from said auxiliary receptacle, a seating band carried by said arms, a main receptacle insertible in said seating band, a carrying band secured about the intermediate portion of the periphery of the main receptacle, bail ears secured to diametrically opposed portions of the carrying band, a bail carried by said ears, and handles secured to portions of the carrying band 60 65 spaced from the ears, said ears and handles being adapted to engage on the seating band.

In testimony that I claim the foregoing I have hereunto set my hand at Milwaukee, in the county of Milwaukee and State of 70 Wisconsin.

ROBERT PERLICK.
